DEVICE FOR LOADING AND EJECTING
CAPSULES

Frederick Koch, Jr., Queens Village, N. Y.

Application June 1, 1936, Serial No. 82,880

6 Claims. (Cl. 226—40)

This invention relates to loading devices and more particularly to an improved and simplified device for loading capsules and the like.

While a great number of capsule filling devices, suitable for hand loading of capsules, have heretofore been devised, they have for the most part not achieved wide or general use for a number of reasons. For example in many cases it is required to load the capsules with powders or other materials which possess an acid characteristic so that when the devices are made out of metal the surface thereof eventually becomes corroded and results in contamination of the filling. If other materials such as wood, fiber and the like are employed they have the additional disadvantage that their surfaces become scored as a result of the continued rubbing pressure required to distribute and force the powder into the capsules. After considerable experimentation I have found that it is possible to construct a capsule filling device which is free from the above-noted and other disadvantages. Accordingly it is one of the principal objects of the present invention to provide a capsule loading device in which at least the powder receiving surface is of a material which is non-metallic, is acid-proof and which is extremely hard. In carrying out this object, I have found that molded synthetic resinous products such as "Catalin" and "Marblette" are eminently well-suited for the purpose.

Another principal object of the invention is to provide a capsule loading device which has a minimum number of movable parts and wherein the capsules may be loaded expeditiously and with accuracy.

A feature of the invention relates to a capsule filling device consisting of two plate-like members capable of simple rectilinear relative sliding movement to effect ejection of the loaded capsules.

Another feature relates to a two-part capsule loading device, one part comprising a slidable perforated platform having integral means to determine accurately the normal spacing of the platforms so that the capsule tops may be dropped into the perforations with the assurance that their edges will not project above the platform, and wherein the ejection of the loaded capsules can be effected by a simple rectilinear sliding movement of the platform. As a result of this feature the use of relatively complicated ejecting means such as screws, cams, inclined guides and the like is completely avoided, thus

increasing the useful life and reliability of the device.

A further feature relates to the novel organization, arrangement and relative location of parts which go to make up a simple, cheaply manufactured and thereby safe device for loading capsules with medicinal powders and the like.

Other features and advantages not specifically enumerated will be apparent after a consideration of the following detailed descriptions and the appended claims.

While the invention will be described herein, as embodied in one particular arrangement of parts it will be understood that this is done merely for explanatory purposes and not by way of limitation thereto. Accordingly in the drawing,

Fig. 1 is a top plan view of the improved capsule loading device according to the invention.

Fig. 2 is a front elevational view of the device of Fig. 1, partly in section along the line 2—2, to show the relation of the parts during loading.

Fig. 3 is a front elevational view of Fig. 1 to show the relation of the parts during ejection of the loaded capsules.

Fig. 4 is an enlarged detail view of one end of the slidable loading platform.

Fig. 5 is a detail sectional view of the slidable blank for controlling the number of capsules to be loaded.

Fig. 6 is a sectional view of Fig. 4 taken along the line 6—6 thereof.

Referring to the drawing, the loading device comprises in general two main parts 1 and 2, the part 1 comprising the supporting base and the part 2 comprising the sliding platform to receive the capsules to be loaded. As shown more clearly in Figs. 2 and 6 the platform 2 carries a set of four pins designated by the numeral 3 for purposes to be described. These pins may be formed integrally with the platform 2 or may be separate members seated and cemented in suitable recesses in the under face of platform 2 as clearly shown in Fig. 6. The base 1 is provided with a set of four platform guiding recesses, each recess comprising a transverse perforation 4 communicating with a longitudinal groove 5 in the upper surface of the base. The guiding recesses are disposed in the base 1 so that they are in registry with the pins 3. The platform 2 is provided with rows of perforations 6 to receive the capsules 7 as indicated in Figs. 55

1, 2 and 3 of the drawing, it being understood that after the capsules are loaded they may be provided with suitable caps 8 as shown in Fig. 3. While the drawing shows the capsule receiving perforations in member 2 all of substantially the same diameter, it will be understood that the perforations may be arranged in groups of different sized perforations to accommodate different sizes of capsules. Preferably the platform 2 is provided around its longitudinal and righthand edges with a raised rim 9 for the purpose of guiding the blank 10 and the powder distributing member 11, the left-hand side of member 11 preferably being inclined as shown in Fig. 2.

15 I have found that the best and most satisfactory results are achieved if the parts above described are made from a hard, non-metallic, acid-proof molded resinous product such for example as "Catalin", "Marblette" or the like, and 20 preferably the molded parts are machined and polished. If desired however, only the platform 2 and the members 10 and 11 which come in actual contact with the loading material may be of this acid-proof resinous product.

25 The manner of employing the device to load capsules with medicinal powders or the like, is substantially as follows. The platform 2 is placed on the base 1 so that the pins 3 are situated at the right-hand ends of the corresponding grooves 5 in which position the platform 2 will be supported in spaced relation to the upper face of base 1 just the right amount so that when the capsules 7 are dropped into the perforations 6 their upper edges are flush 35 with or are very slightly below the upper surface of platform 1, as shown in Fig. 2. The blank 10 is then placed upon the platform 1 to block off the perforations not containing capsules, and while the drawing shows the member 10 as rectangular it may, if desired, be in the form of an 40 L. The member 11 is moved to the left in accordance with the number of rows of capsules to be filled, whereupon a quantity of the powder is placed on platform 2 in the space between members 10 and 11. Member 11 is then moved 45 to the left to distribute the powder over the capsules and the inclined left-hand edge of member 11 entrains and forces the powder downwardly into the capsules. The movement of member 11 also levels off the powder in each 50 capsule so that just the right amount is loaded therein. When the capsules have been properly loaded, the member 11 is moved to the right, and the platform 2 is slid to the left until the pins 3 register with the perforations 4 whereupon the platform 2 drops to the position shown 55 in Fig. 3, in which position the capsules are partially ejected as shown in Fig. 3, and suitable caps 8 may be applied thereto. When the 60 capsules have been capped they may be removed individually by hand. However, if desired, the loaded capsules may be lifted bodily with the member 2 since the perforations 6 may be slightly smaller than the outside diameter of the caps 8. The device is then ready to receive and load another batch of capsules in 65 the manner above-described.

While specific arrangements and proportions of parts have been disclosed herein various 70 changes and modifications may be made therein without departing from the spirit and scope of the invention. Thus instead of providing a single platform 2 with different size perforations for different size capsules, all the perforations 75 may be of the same size in any given platform,

and a series of similar platforms with different size perforations may be employed. Likewise a series of separate platforms similar to platform 2 may be employed with pins similar to pins 3 but of different length to correspond to the length of the capsules to be loaded. As another alternative the pins 3 may be removable so as to be replaced with pins of different length in accordance with the length of the capsules to be filled. Preferably however the pins 3 are permanently fastened in place as above-described and separate platforms with longer or shorter pins are employed.

What I claim is:

1. In a device of the character described, the combination of a slidable platform having a perforation to receive a capsule to be loaded, a base on which said platform is mounted for horizontal sliding movement said platform having a plurality of depending projections adapted to ride on the base to support said platform, a predetermined distance from said base during its horizontal sliding movement, said base having a plurality of recesses with which said projections are registrable to control the ejection of the loaded capsule.

2. In a device of the character described, the combination of a slidable platform having a plurality of perforations to receive capsules to be loaded, a base for supporting said platform and capsules during loading, a plurality of downwardly depending projections on said platform for normally spacing the platform and base a predetermined distance apart and for maintaining said spacing uniform during the sliding movement of said platform, means on said base for guiding said platform during its sliding movement, said base having a plurality of recesses registrable with said projections to allow said platform to fall vertically under its own weight to eject the capsules.

3. In a device of the character described, the combination of a slidable member having a perforation to receive a capsule to be loaded, another member serving as a supporting base over which the first member is arranged to slide, one of said members having a pair of projections slidably engaging the other member when said members are in capsule loading position to space said members a predetermined distance apart, the other of said members being provided with recesses corresponding in number to said projections to allow said members to move toward each other only when said projections are in registry with said projections, said other member being also provided with means forming a pair of parallel guiding edges to engage said projections to guide said slidable member during its sliding movement.

4. In a device of the character described, the combination of two relatively slidable members at least one of which is of a hardened acid-proof resinous material, pins carried by one of said members to space said members apart during capsule loading while allowing said members to slide relatively to each other for capsule ejection, the other of said members being provided with grooves in which said pins ride during said sliding movement, and also being provided with recesses for receiving said pins to allow said members to approach each other only when said members are in capsule ejecting position.

5. In a device of the character described, the combination of a pair of relatively slidable mem-

bers, one of said members having a plurality of capsule receiving perforations, supporting and guiding pins carried by one of said members, the other member being provided with compound recesses registering with said pins, each of said recesses comprising a longitudinal recess communicating with a transverse recess, said longitudinal recesses serving as guides during the relative sliding of said members.

10 6. In a device of the character described, the combination of a pair of relatively slidable members, one of said members having a plurality of capsule receiving perforations, supporting and

guiding projections carried by one of said members and slidably engaging the other member to maintain said members uniformly spaced during their relative sliding movement, the said other member being provided with oppositely disposed parallel guiding edges to guide said one of said members during sliding movement and also being provided with recesses extending perpendicular to the face thereof to allow said members to approach each other only when said projections enter said recesses.

FREDERICK KOCH, Jr.
